UNITED STATES PATENT OFFICE.

CLAS J. JULSTEDT, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

BREECH MECHANISM.

Application filed July 22, 1921. Serial No. 486,757.

To all whom it may concern:

Be it known that I, CLAS J. JULSTEDT, a citizen of the United States, and residing at Bethlehem, Lehigh County, State of Pennsylvania, have invented certain new and useful Improvements in Breech Mechanisms, of which the following is a specification.

The present invention relates to breech mechanisms and particularly to such mechanisms for guns having axially insertable and removable breech blocks, as distinguished from laterally sliding breech blocks, and in which the projectile is propelled by gases generated by the burning of powder or other explosives placed loosely within the powder chamber and not confined within a casing, as in fixed ammunition.

Breech loading guns utilizing loose or uncased explosive charges are necessarily provided with one of the several well known types of obturating devices designed to prevent the escape of gases through the breech when the gun is fired and to eliminate the scouring and destructive effects of such gases escaping at high temperatures and pressures. Devices of this character, such as the well known De Bange obturator, are secured to the front of the breech block and necessarily project forwardly a considerable distance from its face into the bore of the gun. Where the breech block is supported on a carrier pivoted to the gun body it has usually been found necessary to have the edge of the obturator pad widely beveled or at a considerable angle to the axis of the gun and the wall of the tube against which the edge of the pad abuts also sloped or beveled to an equal degree so that the free swinging action of the block in loading and unloading the gun is not interfered with. It is desirable however to have the edges of the gas check pad as nearly as possible parallel to the axis of the gun as it has been found that destructive gas leakage occurs when the annular wall of the gas check pad and the seat in the powder chamber against which it abuts, makes a rather large angle with the gun axis or, as commonly stated, has a "steep slope."

The object of the present invention is to provide a breech mechanism for a breech loading gun having a swinging breech block provided with a gas obturating device, in which the slope of the edge of the gas check

pad and the seat therefor in the powder chamber, relative to the axis of the gun, is very slight, but at the same time the freedom of swinging movement of the breech block is not interfered with. The invention may have various embodiments and in the accompanying drawings one form is illustrated by way of example. In the drawings:

Figure 1 is a top plan view of the breech end of a gun showing the improved breech mechanism with the breech open and the breech block swung aside;

Figure 2 is a horizontal section through the breech end of the gun, the breech being closed;

Figure 3 is a rear elevation of the gun; Figure 4 is a side view of the breech end as viewed from the right (Figure 3);

Figure 5 is a section on line 5—5 of Figure 3, the breech being open; and

Figure 6 is a section on line 6—6 of Figure 3 with the breech open.

The gun body may be of any well known design having a single tube or built up of concentric tubes, or wire wrapped, and may be of the rifle, howitzer or mortar type. In the drawings the gun body is shown to comprise two concentric tubes 10 and 11 the interior of the rear end of the inner tube 11 comprising a powder chamber, adapted to receive uncased explosive material. The breech recess 12 is adapted to be closed by the cylindrical breech block 13, the block and recess having the well known interrupted thread interengagement so that the block may be locked and unlocked by rotating it through $\frac{1}{6}$ th or $\frac{1}{8}$ th or other fraction of a revolution depending upon the number of segments into which the threads of the block and recess are divided.

The block has an axial aperture 14 which receives a tubular spindle 15 extending forwardly from the carrier 16. This spindle is provided with external threads 17 which engage corresponding internal threads of the breech block, these threads having the same pitch as interengaging threads of block 13 and breech recess 12. The spindle 15 is non-rotatable while the block may be freely rotated in being locked and unlocked. Extending through the tubular spindle 15 is a second spindle 18 having a mushroom head 19 and which comprises, together with the gas check pad 20 of asbestos, tallow,

paraffine or other substance, and the customary split rings, an obturator of the De Bange type. The gas check pad 20 is frusto-conical, its side wall making a small angle with the axis of the gun and that portion of the powder chamber which contacts with the annular wall of the gas check pad being also correspondingly inclined to the axis of the gun. Spindle 18 is axially movable relatively to the breech block and upon firing the gun it is pressed rearwardly and exerts a strong pressure on the pad 20 which expands radially and prevents the escape of gas past its edges in the well known manner.

The means for rotating the block 13 in locking and unlocking the same includes a cross head 21 slidably in a longitudinally extending guide 22 rigidly secured to the breech block, and an operating lever 23 connected by means of a shaft 24 having a crank 25 and crank pin 26, to the cross head. Movement of the lever 23 toward the left (Figure 4) will rotate the block in a counterclockwise direction and disengage its threads from the threads of the breech recess, and movement in the opposite direction after the threads have been disengaged causes the threads of block and recess to mutually engage.

The carrier 16 has a forwardly extending arm 27 which is pivotally connected at its forward end to a link 28 by means of a pin 34, the link 28 being in turn pivotally secured to the gun body by a vertically disposed pin 29. The link 28 lies in an outwardly flaring transverse slot 30 and may have a swinging motion about the pivot 29 from the position in which it is illustrated in Figure 2 to the positions in which it is illustrated in Figures 5 and 6. The carrier and breech block may therefore be moved axially of the gun, when the breech is unlocked, through a distance determined by the extent of movement of the link 28.

The upper and lower surfaces of arm 27 are provided with cam grooves 31 to receive the upper and lower rollers 32 secured to the gun body. These rollers are coaxial and serve to guide the carrier in its longitudinal movements, the cam grooves being designed to prevent the block from swinging until its translatory movement is completed and being so shaped that substantially axial movement of the block during the swinging movement of the link is assured. The arm 27 has extensions 33 the ends of which are curved about the axis of the bolt 34 as a center. When the breech is closed these extensions lie in the positions illustrated in Figure 2.

Assuming the breech to be closed and it is desired to open the same the handle or operating lever 23 is moved rearwardly. The initial movement of the handle causes

rotation of the breech block, which is unlocked. As the breech unlocks it moves rearwardly axially a short distance relatively to the gun and carrier due to its threaded engagement with these members and at the conclusion of the unlocking movement it is given a further substantially axial rearward movement by continued rearward pull upon the operating lever, which causes the carrier to draw link 28 toward the rear, rotating it about pivot 29, the breech block and carrier moving bodily towards the rear to a distance determined by the extent of movement of the link 28 in the slot 30.

When the limit of this rearward movement is reached, that is when the link has reached the position illustrated in Figures 5 and 6, the operating handle 23 is in a substantially horizontal position extending rearwardly and a slight pressure from left to right on this handle is then sufficient to swing the carrier about pivot 34 so that the block is swung to the side as shown in Figure 1, in which position the gun may be freely examined and re-loaded. In this lateral swinging movement the extensions 33 of arm 27 enter the slot 30 and their rounded ends contact with the wall of this slot so that forward movement of the carrier and block is positively prevented until the block has been again swung into substantial axial alignment with the gun axis. In closing the action is reversed, the block swinging about the pivot 34 through an angle of substantially 90° and then the block and carrier being moved bodily forward when the extensions 33 have disengaged the slot 30, as the link 28 swings about the pivot 29.

The initial rearward movement of the carrier and block in opening the breech and the final forward movement of these members in closing the breech is controlled by the cam grooves 31 and rollers 32 which are so formed as to constrain the block and carrier to move in an almost straight line until the link 28 has completed its forward or rearward swing. During the early part of the swing of the breech block about the pivot 34 in opening, the rollers 32 are still engaged in cam grooves 31 and all possibility of the link 28 starting to swing back to its original position, is positively prevented. After a small angle of swing has been accomplished and before the rollers have emerged beyond the ends of the cam grooves the extensions 33 have entered the slot 30 and forward movement of the link 28 positively prevented. In Figure 1 the paths of the opposite edges of the obturating device are indicated in dotted lines.

It is desirable, especially in mobile field guns to provide means for preventing, as far as possible, the entrance of dust and grit into the joints between the moving parts of

- the breech mechanism, which causes jamming and excessive wear. To keep grit from entering the slot 30 in the present instance, and penetrating to the breech threads, a plate 35 is provided, this plate having a tongue 36 which is pivoted on bolt 34. As the carrier moves axially the plate 35 also moves and, together with extensions 33, forms a complete closure for the outer end of slot 30. A shoulder 37 on the plate also serves as an abutment, limiting the swinging movement of the carrier 27, which has a cooperating abutting surface 38. A pocket 39 is bored in link 28 obliquely to the major axis, and the periphery of the tongue 36 is cut away to form an abutment 40 for a coil spring 41 lying in said pocket, so that at all times the plate 35 is held in sliding dust tight contact with the tube 10.
- It will be seen that the initial opening movement and the final closing movement of the device are practically along straight lines parallel to the axis of the gun. It is therefore unnecessary to bevel the annular edges of the gas check pad so that they make a large angle with the axis of the gun which leads, as before explained, to the escape of destructive gases under high temperatures and pressures.
- Having thus described my invention what I claim as new and desire to secure by Letters Patent is:
1. A breech mechanism comprising in combination, a breech block, a carrier therefor, and a link secured to said carrier and adapted to be secured to the tube of a gun and to extend transversely of the latter whereby the block may be given first an axial movement and thereafter an arcuate movement in opening the breech recess.
  2. A breech mechanism, comprising in combination, a breech block, and means for supporting the breech block on the tube of a gun, said means including a carrier for the block, and a member adapted to be pivoted to the tube and to extend transversely of the latter and pivoted to the carrier whereby the carrier may be moved first longitudinally and then laterally of the tube, for the purpose set forth.
  3. In a breech mechanism, in combination, a breech block, and means adapted to support the breech block on the tube of a gun including a carrier on which the block is rotatably mounted and a link extending transversely of the tube adapted to be pivotally connected to the tube and to one end of the carrier so that the latter may be swung laterally and moved axially relatively to the gun when opening and closing the breech, the link rotating in the opening and in the closing movement in a direction opposite to the direction of rotation of the carrier.
  4. In a breech mechanism, in combination, a breech block, a carrier for the block having a cam groove, means adapted to support the carrier on the tube of a gun for lateral swinging movement and movement axially of the gun, and means including a member adapted to be secured to the tube and to engage the cam groove in the carrier, for guiding the carrier in its axial movements.
  5. In a breech mechanism, in combination, a breech block, a carrier for the block, means adapted to support the carrier on the tube of a gun for lateral swinging movement and movement axially of the gun, and means including a roller adapted to be supported on the tube and to engage the carrier for guiding the carrier in its axial movements.
  6. In a breech mechanism, in combination, a breech block, a carrier for the block having cam grooves in its upper and lower surfaces, means adapted to be secured to the tube of a gun for supporting the carrier for lateral and substantially axial movement relatively to the gun, and rollers adapted to be secured to the gun and to extend into the cam grooves of the carrier to guide the same in its axial movement.
  7. A breech mechanism comprising, in combination, a breech block, a carrier therefor, means for supporting the carrier on the tube of a gun for lateral swinging movement and movement axially relatively thereto, and means on the carrier for locking the carrier against axial movement while it is being swung laterally.
  8. In a breech mechanism, in combination, a breech block, means secured to the block and adapted to be secured to the tube of a gun for supporting said block for lateral swinging movement and axial movement relatively to the tube, means for locking the block against swinging movement while it is being moved axially, and means for locking the carrier against axial movement while it is being swung laterally.
  9. In a breech mechanism in combination, a breech block, means for supporting the breech block on the tube of a gun for lateral swinging movement and movement axially relatively thereto including a carrier, and means for locking the carrier against axial movement while it is being swung laterally, said means comprising an extension on the carrier adapted to engage the tube when the lateral movement of the carrier is begun in opening the breech and to remain in engagement with the tube until the swinging movement of the carrier in closing the breech has been substantially completed.
  10. In a breech loading gun, the combination with the tube and breech block of a carrier supporting the breech block on the tube and mounted for lateral swinging movement and movement axially of the gun, and means for locking the carrier against axial movement.

- axial movement while it is being swung laterally.
11. In a breech loading gun, the combination with the tube and breech block of a carrier supporting the breech block on the tube and mounted for lateral swinging movement and movement axially of the gun, means for locking the carrier against swinging movement, while it is being moved axially, and means for locking the carrier against axial movement while it is being swung laterally.
12. In a breech loading gun, in combination, a tube having a radial slot therein, a breech block, a carrier for the breech block, means for supporting the carrier on the tube including a member movably supported in said slot, and a plate connected to said member and movable therewith and normally extending across the mouth of said slot to exclude dust therefrom.
13. In a breech loading gun, in combination, a tube having a radial slot therein, a breech block, a carrier for the breech block, a link pivotally supported in said slot, a pin pivotally connecting the link and carrier, a plate pivotally supported on said pin and normally extending across the mouth of said slot to exclude dust therefrom.
14. In a breech mechanism, in combination, a breech block, a carrier therefor, means adapted to support the carrier on a gun tube including a member movable axially of the gun and adapted to be secured in a recess in said tube, and means secured to said member for excluding dust from said recess.
15. In a breech mechanism, in combination, a breech block, a carrier therefor, means adapted to support the carrier on a gun tube including a member movable axially of the gun and adapted to be secured in a recess in said tube, and means comprising an axially disposed plate pivotally secured to said member and extending across the mouth of the recess, for excluding dust therefrom.
16. In breech mechanism for a gun, the combination of a carrier, a breech block on the carrier, said carrier including an arm arranged substantially parallel to the block, and a link pivotally connected at its outer end to said arm and extending transversely of the arm and block and adapted to be pivotally connected at its inner end to a gun tube.
17. In breech mechanism, the combination of a carrier, a breech block on the carrier, said carrier including an arm arranged substantially parallel to the block, a pivot for the arm, and a lug on the arm and arranged forwardly and laterally of the pivot, said lug having a curved surface which is coaxial with the axis of the pivot.
18. In breech mechanism, the combination of a carrier, a breech block on the carrier, said carrier including an arm arranged substantially parallel to the block, a pivot for the arm, and a lug extending forwardly and laterally of the pivot and having a curved surface coaxial with the axis of the pivot, said arm having a cam groove entering laterally thereof and including a portion which is coaxial with the pivot and a portion which extends diagonally of the arm.
19. In a gun, the combination of a gun tube, a breech block for a tube, a carrier for the breech block, a link pivoted at its inner end to the tube and capable of swinging motion longitudinally of the tube, and a pivotal connection between the outer end of said link and the carrier.
20. In a gun, the combination of a gun tube, a breech block for the tube, a carrier for the breech block, a link pivoted at its inner end to said tube and extending laterally therefrom, means for limiting swinging motion of the link longitudinally of the tube, and a pivotal connection between the outer end of said link and the carrier.
21. In a gun, the combination of a gun tube, a breech block for the gun, a carrier for the breech block having an arm arranged substantially parallel to the block, said tube having a slot at its breech end which flares outwardly, a link pivotally connected to the tube at the inner end of the slot, and a pivotal connection between the outer end of the link and said arm.
22. In a gun, the combination of a gun tube, a breech block for the tube, a carrier for the breech block having an arm arranged substantially parallel to the block, said tube having a laterally-extending slot at the breech end thereof which flares outwardly, the forward side of said slot terminating in a curved surface, a link pivotally connected to the tube adjacent to the inner end of the slot, a pivotal connection between the outer end of the link and said arm, and a lug arranged forwardly and laterally of the pivotal connection and having a curved surface which is coaxial with the axis of said connection, whereby the link is maintained in its rearmost position when the carrier is swung about the pivotal connection.
23. In a gun, the combination of a gun tube, a breech block for the tube, a carrier for the breech block having an arm arranged substantially parallel to the block, said tube having a lateral slot near the breech end thereof which flares outwardly and the forward side of said slot terminating in a curved surface, a link arranged in the slot and pivotally connected to the tube adjacent to the inner end of the slot, a pivotal connection between the outer end of the link and said arm, a lug carried by the arm and extending forwardly and laterally of the

pivotal connection, said lug having a curved surface coaxial with the axis of the pivotal connection, said arm having a cam slot arranged rearwardly of the pivotal connection and said slot including an entrance portion which is substantially coaxial with the axis of the pivotal connection and a diagonal portion, and a stationary member carried by the gun tube for engagement in said cam slot.

24. In a gun, the combination of a gun tube, breech mechanism including a breech block and an obturator, a carrier for the breech block and the obturator, a link pivotally connected at its inner end to the gun tube and extending transversely thereof and capable of limited swinging motion longitudinally of the tube, said link extending slightly forwardly of the normal to the tube passing through the axis of the pivot for the link when the obturator is seated, a pivotal connection between the link and the carrier, a guide connection between the tube and the carrier, whereby, when the latter tends to move laterally due to rearward motion of the link, the obturator is caused to travel in substantially a straight line, and a lever swingable in a plane to connect and disconnect the breech block and to secure forward and rearward motion of the block, carrier, and obturator, said lever being capable of being swung in another plane when

the block, carrier and obturator are at the limit of their rearward motion to swing said carrier about its pivotal connection. 35

25. In a gun, the combination of a gun tube, a carrier, an obturator connected to the carrier, a breech block, a mutilated thread connection between the breech block and the gun tube, a threaded connection between the breech block and the carrier having the threads thereof extending in the same direction as the mutilated threads, a shaft carried by the carrier, means for transmitting rotary motion of said shaft to the breech block to rotate the latter to connect and disconnect the mutilated thread connection, a link pivotally connected to the gun tube and capable of swinging motion to a limited extent longitudinally of the tube, a pivotal connection between the link and the carrier, and a lever connected to said shaft and swingable in one plane to rotate the shaft for engaging and disengaging the mutilated thread connection and for moving the carrier and obturator forwardly and rearwardly with respect to the tube and swingable in another plane when the obturator and carrier are retracted to swing the carrier about its pivotal connection. 40 45 50 55 60

In testimony whereof I hereunto affix my signature.

CLAS J. JULSTEDT.
